DESIGN FOR A COMBINED REMOTE CONTROLLER AND LOUD-SPEAKER CASING

Lloyd J. Andres, Chicago, Ill.

Application February 17, 1940, Serial No. 90,340

Term of patent 7 years

To all whom it may concern:

Be it known that I, Lloyd J. Andres, a citizen of the United States and resident of Chicago, in the county of Cook and State of Illinois, have invented a new, original, and ornamental Design for a Combined Remote Controller and Loud-Speaker Casing, of which the following is a specification, reference being had to the accompanying drawings, forming part thereof.

Figs. 1 and 2 are front and side elevations of the combined remote controller and loud-speaker

casing respectively, showing my new design. Fig. 3 is a top view of the casing.

The characteristic features of my design reside in the portions shown in solid black lines in the drawings.

I claim:

The ornamental design for a combined remote controller and loud-speaker casing, as shown and described.

LLOYD J. ANDRES.
